UNITED STATES PATENT OFFICE.

ALEXANDER DOM, OF MOUNT HEALTHY, OHIO.

MAP AND CHART EXHIBITOR.

SPECIFICATION forming part of Letters Patent No. 257,671, dated May 9, 1882.

Application filed October 18, 1881. (No model.)

To all whom it may concern:

Be it known that I, ALEXANDER DOM, of Mount Healthy, Hamilton county, State of Ohio, have invented certain new and useful Improvements in Map and Chart Exhibitors, of which the following is a specification.

The object of my invention is to provide a convenient and cheap device for displaying maps, charts, show-cards, or other display-sheets for use in schools or libraries. It is especially applicable to displaying alphabetical and primary charts and small maps for primary schools, but is not confined in its usefulness to this class of display-sheets.

Referring to the drawings making part of this specification, Figure 1 is a perspective view of my invention. Fig. 2 is a perspective view of a detached portion. Fig. 3 is an enlarged central vertical section of the upper portion, taken at right angles to the roller. Figs. 4 and 5 represent modifications of my invention.

A is the standard, suitably upheld. In the present instance it rests upon three or more legs, *a*. Upon the top of this standard is supported the frame A'. This frame consists of the horizontal rail B and the arms B'. The rail B is provided at its center with the pin *b*, which, when the parts are all in position, enters a hole, *b'*, in the top of the standard A, as shown in Fig. 3. This hole *b'* is sufficiently large to allow the pin *b* to turn freely therein, so that the frame A', to which the pin *b* is attached, may be caused to revolve on top of the standard, the pin *b* extending far enough into the top of the standard A to give a firm support to the frame A'. A rail, C, is fixed to or suitably journaled in the arms B'. The preferable form of said rail is that of a roller, as shown, and the preferable mode of connecting it to the standard is as follows: The top ends of the arms B' are provided with notches *d*, in which rests the axis of the roller C. If preferred, only one of the arms B' need be provided with a notch, the other arm having a hole into which one end of the axis of the roller C is placed, the purpose of these notches being to allow of a ready removal and insertion of the roller into the frame A'. Around the roller C, at intervals, are attached the maps or charts E, as shown in Fig. 3. A strip

of muslin, X, or other strong cloth is attached to each sheet along its upper edge, and it is by this strip that each sheet is attached to the roller or rail, thus preventing the tearing of the sheets as they are handled. These maps or charts are preferably printed on both sides to economize space, and the construction of the frame A' and standard A is such as to permit of the ready inspection of either side, 55 it only being necessary to revolve the frame A' one-half around.

To give a better understanding of my invention, I will describe its mode of operation.

The maps, charts, or diagrams to be studied 65 are attached to the roller C, as described, and the roller is placed in the frame A'. In the present instance I have a series of primary charts, one of them, illustrating lesson five, being ready for inspection. If, now, it is desired 70 to examine lesson six, which is on the reverse side of the sheet bearing lesson five, this sheet is thrown over to the other side of the frame and the frame turned one-half around, which will bring lesson six to the position now occupied by lesson five, and by turning the frame back again lesson seven will be visible, it having been uncovered when the sheet bearing lessons five and six was thrown over the frame. In this manner any desired lesson may be 75 brought into view, the roller C, as the various sheets are thrown over, turning slightly, so that the outside sheets always hang from the top of the roller, as shown in Fig. 3. The cloth strip X, interposed between the display-sheets and the roller, permits the several sheets to be readily thrown over the frame and prevents the sheets from being torn. By this means the sheets do not become injured by folding or rolling, and a great number of sheets 85 may be attached to one roller, thus greatly economizing room, and also making it much more convenient for the examiner than where he has to hang each sheet separately on a frame.

My invention will be found very useful and 95 convenient for schools, as it is very compact and portable, and is easily managed. While I have in the present instance represented my invention as applied to displaying a series of primary charts, it will be perfectly obvious 100 that any description of chart, map, diagram, illustration, or other display-sheet may be ad-

vantageously displayed, and I do not therefore confine myself to the use of any particular map or chart.

The connection between the standard A and frame A' may, if desired, be somewhat varied and yet fall within the scope of my invention, the purpose of this feature being to give a firm support to the frame and yet allow it to turn freely. For instance, the standard A may be 10 made of a metal rod the top of which shall pass up into a hole in the frame A'; or one end of the pin b may be firmly held in the top of the standard A, the other end entering a hole in the frame A'.

15 A modification of my invention is shown in Fig. 4, representing a substitute for the frame A' and standard A. In this modification the roller C is made hollow and has passing through it the horizontal arm of the crane 1, 20 this crane being secured to the strip or bracket 2, which is to be secured to the wall; or the crane may be secured directly to the wall. In this instance the crane is moved from side to side to display the different faces of the sheets 25 attached to the roller C.

Another slight modification is shown in Fig. 5, in which the arms B' and roller C are dispensed with and the display-sheets are to be attached directly to the rail B, in which event the 30 cloth connecting-strips should be somewhat wider than shown in Fig. 3 to permit the display-sheets to hang smoothly.

What I claim as new and of my invention, and desire to secure by Letters Patent, is—

35 1. In combination with a series of display-sheets, a frame or support to which one end of

said sheets is attached, said frame being retained on an appropriate support and capable of being turned horizontally thereon, substantially as and for the purposes specified. 40

2. The roller C, having attached thereto a series of display-sheets, E, and supported by a frame, said frame being retained on an appropriate support and capable of being turned horizontally thereon, substantially as and for the purposes specified. 45

3. The standard A, provided at the top with hole b', and frame A', consisting of the horizontal rail B and arms B', the frame being provided with pin b and capable of being 50 turned horizontally on the standard, in combination with the roller C, having attached thereto at intervals around its face a series of display-sheets, E, substantially as and for the purposes specified. 55

4. The standard A and frame A', capable of being turned horizontally on the top of the standard, said frame being further provided with notches d, in combination with the roller C, having attached thereto a series of display-sheets, substantially as described. 60

5. The rail C, retained on an appropriate support and capable of being turned horizontally on such support, and a series of display-sheets attached to said rail by means of a connecting-strip, X, substantially as and for the purposes specified. 65

ALEXANDER DOM.
